UNITED STATES PATENT OFFICE.

PHILLIPP F. FLAGGE, OF DUBUQUE, IOWA, ASSIGNEE TO KLAUER MANUFACTURING CO., OF DUBUQUE, IOWA.

INTERLOCKING CAP FOR ROLLS.

Application filed January 16, 1923. Serial No. 612,981.

To all whom it may concern:

Be it known that I, PHILLIPP F. FLAGGE, a citizen of the United States, and resident of Dubuque, in the county of Dubuque and 5 State of Iowa, have invented certain new and useful Improvements in Interlocking Caps for Rolls; and I do hereby declare that the following is a full, clear, and exact description thereof.

10 This invention relates to interlocking caps for hollow rolls of sheet material, and although adapted for a variety of uses, is particularly directed to an interlocking cap for roofing rolls.

15 In roofing rolls as heretofore constructed, it has been customary to either leave the interior hollow portions open or else to close them by means of tapered plugs drawn towards each other by a bolt extending longitudinally thru the roll. This latter practice has, however, the serious objection of 20 obstructing the space within the roll which prevents the ready storing of material within such hollow space and otherwise provides 25 a bulky construction.

This invention is designed to overcome the above noted defects and objects of such invention are therefore to provide an interlocking cap for rolls which does not obstruct 30 the interior of the roll, and in which each cap is a complete entity in itself and does not require a longitudinal member thru the entire roll to the other cap.

Further objects are to provide an interlocking cap for a roll of roofing material which seals the outer end of the roll and is held in firm engagement therewith by expandable means carried upon the inner side of such cap; to provide interlocking caps 40 which are complete in themselves; to provide interlocking caps with means upon their exterior whereby the expandable means positioned interiorly of the roll may be manipulated to engage the interior surface and 45 hold the cap in position.

An embodiment of the invention is shown in the accompanying drawings, in which—

50 Figure 1 is a longitudinal sectional view thru a roofing roll showing the caps in position, such roll, however, being shown broken away for ease of illustration.

Figure 2 is a view from the inner side of one of the interlocking caps.

55 Referring to the drawings, it will be seen

that a roll 1 of ordinary roofing material, provided with a hollow interior 2 has been illustrated. End caps which interlock with the interior of the roofing roll and abut the outer end faces thereof are shown in position in Figure 1. These caps comprise an annular flange 3 provided with a cup shaped body portion which may consist of a cylindrical portion 4 of slightly less diameter than the hollow portion 2 of the roll, and 60 with the upwardly bulged conical central portion 5.

Upon the inner side of this conical portion, any suitable expandable means may be provided and in the form illustrated, a 70 spring spider having a central portion 6 and angularly arranged arms 7 is shown. The spring arms are preferably provided with inturned gripping ends 8 and with a rectangular recess 9 in its central portion 6. 75 A bolt 10 is passed thru the spider and thru the conical portion 5 of the cup-shaped end closure member, and is so positioned that its head 11 is socketed within the rectangular recess 9 to thereby prevent the bolt from 80 turning. The upper threaded portion 12 of the bolt, which projects outwardly beyond the central portion of the cup-shaped member, is provided with a nut 13. When this nut is tightened the spring arms are forced 85 into interlocking engagement with the interior surface of the roll and the end closure cap is firmly held in an inwardly drawn manner. Any attempt to pry the cap off results in a firmer gripping of the arms and 90 frustrates such attempt.

It is preferable in forming the annular flange 3 to provide such flange with a series of corrugated portions, as indicated at 14, to both strengthen the flange and to aid in the 95 firm engagement of the flange with the ends of the roll. It is obvious that if it is desired the spring arms 7 may be reinforced adjacent the central portion 6 by suitable means, as, for instance, reinforcing ribs, 100 thickened portions, or in any desired manner.

Although one expandable means has been shown, it is intended that any desired expanding means may be used as will come 105 within the terms of the appended claims for instance, expandible bolt construction might be employed.

It will be seen, therefore, that interlocking roofing roll caps have been provided which 110

are adapted to seal the ends of the rolls without obstructing the interior hollow portions thereof, and that such caps may be formed in a sturdy, rugged and simple manner.

5 Although the invention has been described in considerable detail, it is to be understood that such invention is to be limited only as set forth in the appended claims.

I claim:

- 10 1. An interlocking cap for hollow rolls of sheet material comprising a closure member having an annular concentric flange adapted to abut the outer end of the roll and a cup shaped body portion adapted for
- 15 positioning within the hollow portion of the roll, an expandible spider having angularly arranged arms mounted upon the end of the cup shaped portion, and a bolt extending through said spider and cup shaped
- 20 portion, whereby when the bolt is tightened, the said spider is flexed and the arms thereof are forced outwardly into binding engagement with the interior of the hollow portion of the roll and the closure drawn

into sealing engagement with the end of the 25 roll.

2. An interlocking cap for hollow rolls of sheet material comprising a closure member having an annular concentric flange adapted to abut the outer end of the roll, 30 and a cup shaped body portion extending inwardly of the roll and integrally formed with said flange, an expandible spider having angularly arranged arms with their upper portions contacting with the lower surface of said cup shaped portion, and a bolt 35 extending through the spider and cup shaped portion, whereby when said bolt is tightened, said arms slide along the under surface of said cup shaped portion and are 40 forced into direct binding engagement with the inner portion of the roll.

In testimony that I claim the foregoing I have hereunto set my hand at Milwaukee, in the county of Milwaukee and State of 45 Wisconsin.

PHILLIPP F. FLAGGE.
